(57) CLAIM

The ornamental design for an outdoor wall light as shown and described.

DESCRIPTION

FIG. 1 is a front perspective view of an outdoor wall light, showing my new design;

FIG. 2 is a front elevational view thereof;

FIG. 3 is a left elevational view thereof;

FIG. 4 is a right side view thereof;

FIG. 5 is a top side view thereof; and,

FIG. 6 is a bottom plan view thereof.

The broken lines in the figures are for the purposes of illustrating portions of the outdoor wall light, which form no part of the claimed design.
